UNITED STATES PATENT OFFICE.

ELIJAH E. DEPUTY, OF EAST DOWNTON, PENNSYLVANIA, ASSIGNOR TO MARSHALL P. DEPUTY, OF EAST DOWNTON, PENNSYLVANIA.

PAPER-ROLLING DEVICE.

1,357,385.

Specification of Letters Patent.

Patented Nov. 2, 1920.

Application filed April 15, 1919. Serial No. 290,243.

To all whom it may concern:

Be it known that I, ELIJAH E. DEPUTY, a citizen of the United States, residing at East Downton, in the county of Chester 5 and State of Pennsylvania, have invented certain new and useful Improvements in Paper-Rolling Devices, of which the following is a specification.

One object of my invention is to provide 10 apparatus which will be particularly adapted for use by barbers for the rolling of small rolls of paper of the character used in the head rests of barber chairs, from a large roll of paper which can be bought 15 commercially in the market.

Another object is to make my invention of a simple construction so that it can be easily carried and set upon a table and when not desired for use can be easily 20 stored.

These objects, and other advantageous ends which will be described hereinafter, I attain in the following manner, reference being had to the accompanying drawings in 25 which—

Figure 1 is a side elevation of my invention in an operative position for winding small rolls of paper, as above described,

Fig. 2 is a transverse sectional elevational 30 view taken on the line 2—2 of Fig. 1, and Fig. 3 is a top plan view of Fig. 1.

Referring to the drawings, my invention includes a frame 7, preferably of metal, which consists of two side pieces or rails 8 35 and 9 which are connected together at their forward and rear ends by end couplings 10 and 11. The couplings 10 and 11 are respectively connected to the rails 8 and 9 by bolts 12. The rail 8 has two standards 13 and 14 40 adjacent the front and rear ends, and the rail 9 has two standards 15 and 16 respectively opposite the standards 13 and 14. The standards 14 and 16 have holes 17 which provide bearings for an axle 18 which 45 supports a large roll of paper 19. A yoke 20 has its free end portions 21 pivotally connected to the oppositely disposed rails 8 and 9 by pivot screws 21^a in such manner that its upper bar portion 22 can be moved 50 into engagement with the forward portion of the roll of paper 19. Coiled tension springs 23 have their ends respectively connected to the yoke 20 and to the frame 7 so as to move and keep the bar portion 22 in 55 engagement with the roll of paper 19, as

clearly shown in Fig. 1. The yoke 20, due to its frictional engagement with the roll of paper 19, prevents the accidental rotation of the roll of paper 19 and also prevents the inertia of said roll of paper 19 60 from causing the paper to be loosened thereon when it is rotated, as will hereinafter be described. The standard 13 has a hole 24 therein and the standard 15 has a vertical notch 25 extending downwardly from its 65 top. The hole 24 and notch 25 respectively form bearings for the opposite ends of a mandrel 26. One end of the mandrel 26 has a handle 27 thereon, whereby the mandrel can be rotated. The end portion 28 of 70 the paper on the roll 19 is adapted to be wound upon the mandrel 26, due to the rotation of said handle 27. In order to prevent the mandrel from rising accidentally within the notch 25 during the rotation of 75 the handle 27, I provide a hook 29 which is pivotally connected at 30 to the standard 15.

To start the rolling of the paper upon the mandrel 26, the end portion 28 is initially pressed, by hand, into engagement 80 with the outer surface of the mandrel and the handle 27 is rotated until the free end of the paper is caught between the mandrel and the first wrapping of the paper. It is then an easy matter to wind the paper upon 85 the mandrel until sufficient paper has been wound thereon for the purpose desired, and then the paper thus wound can be freed of the mandrel by releasing the hook 29 and raising the mandrel out of the notch 25. 90 The opposite end of the mandrel can then be pulled out of the hole 24 and the paper thus rolled can be freely slid longitudinally off the mandrel. It will be noted, however, that the paper thus rolled is still integrally 95 connected to the paper on the roll 19. To sever the paper thus rolled, from the roll 19, it is merely necessary to slightly raise the portion 28, and the front edge 31 of the bar 22 of the yoke 20 will serve as a tearer 100 or knife and thereby sever the portion 28 from the paper on the roll 19. Fig. 1 shows in dot-and-dash line position the portion 28 and the portion 32 of the paper as rolled on the mandrel 26, when ready to be torn with 105 the edge 31 of the yoke 20 as a cutter.

Also by making the frame 7 of separate and detachable parts the entire structure can be shipped knocked down.

While I have described my invention as 110

taking a particular form, it will be understood that the various parts of my invention may be changed without departing from the spirit thereof, and hence I do not 5 limit myself to the precise construction set forth, but consider that I am at liberty to make such changes and alterations as fairly come within the scope of the appended claim.

10 Having thus described my invention, what I claim as new and desire to secure by Letters Patent is:—

A device of the character described including a supporting frame; a roll of sheet 15 paper mounted on said frame; an inverted substantially U-shape yoke having the free ends of its legs pivoted to the opposite sides of said frame and its transverse portion adapted to engage said rolled paper; means 20 for re-rolling the paper from said roll; and resilient means connected to said frame and having a portion secured to each leg of said

yoke between said transverse portion and the pivotal connections of said yoke with the frame, said resilient means being operative 25 to move the transverse portion of the yoke into engagement with the roll so that substantially similar tension will be placed upon said transverse portion adjacent both ends whereby it will be kept in direct engagement 30 with said rolled paper throughout its width and the yoke can be made of comparatively narrow and light weight metal, said transverse portion of the yoke serving as a straight edge for tearing the paper and for 35 holding the paper in the roll while being re-rolled therefrom; substantially as described.

In testimony whereof I have signed my name to this specification in the presence of two subscribing witnesses.

ELIJAH E. DEPUTY.
